UNITED STATES PATENT OFFICE.

OSCAR SIMMERSBACH, OF BRESLAU, GERMANY.

OPEN-HEARTH FURNACE.

1,090,503.

Specification of Letters Patent. Patented Mar. 17, 1914.

Application filed August 31, 1912. Serial No. 718,015.

To all whom it may concern:

Be it known that I, OSCAR SIMMERSBACH, a subject of the German Emperor, and resident of Breslau, Germany, have invented 5 certain new and useful Improvements in Open-Hearth Furnaces, of which the following is a specification.

My present invention relates to reverberatory furnaces of the Siemens-Martin type, 10 the Talbot type, or like construction. Such furnaces were formerly heated, as a rule, by means of producer gas, which is relatively poor in hydrocarbons, but the recent practice has been to employ gases relatively rich 15 in hydrocarbons, for instance the gases produced in coke ovens. In passing through the furnace chamber, this gas tends to rise to the roof or top wall of the furnace, thus exposing the furnace arch to destruction, 20 particularly as the combustion of coke oven gases produces a much higher temperature than the combustion of producer gas. Hitherto it has been endeavored to throw 25 the flame down upon the molten metal as far as possible, by giving a correspondingly strong inclination to the air-supply channels which are located above the gas-supply channels. This arrangement, however, is 30 not very successful in the case of large furnaces supplied with cold fuel (gas), since the flame will be thrown down only in the part or half of the furnace nearest the fuel and air inlets. In the second half of the 35 furnace the gas rises again, since the waste-gases proceed to the regenerator on that side of the furnace which is temporarily the outlet side, only through the air-supply channel, which, as stated, is located at a high level. In order to avoid these drawbacks, 40 I have supplied reverberatory furnaces of the type named (Martin, Talbot, or the like), with auxiliary air-supply channels, or with a single such channel, located laterally of the customary fuel-supply channel 45 or channels, it being understood that these auxiliary channels are additional to the gas-supply channel or channels and to the customary air-supply channel or channels located at each end or head of the furnace, 50 above the fuel-supply channel or channels.

With this novel arrangement, the waste-gases can pass out, not only through the main air-supply channel located in the upper part of the furnace head, but also 55 through the auxiliary air-supply channels situated but slightly above the level of the

molten metal. The flame is thus compelled to travel close to the surface of the metal, even in the part of the furnace adjacent to the outlet, and is prevented from rising to 60 the arch or roof and destroying it. The provision of these auxiliary air-supply channels also insures a thorough and rapid mixture of the fuel or heating gas with the air provided to support combustion, and the 65 combustion of the mixture is thus promoted, so that the gases will be consumed completely within the furnace and cannot pass out in an imperfectly consumed condition into the head at the opposite side of the 70 furnace, with the attending danger of combustion occurring in the furnace head or even in the regenerators, which of course would be highly detrimental to the heads and end or face walls of the furnace. The 75 improvement in the mixture and combustion within the furnace has the further advantage of reducing the interval of time between successive charging operations.

Another feature of this invention consists 80 in the provision of one or more dampers or other devices for throttling the passage of the gases through the main air-supply channel. These dampers or throttling devices are preferably arranged in the air-distributing channel provided in each furnace head, or in the main air-supply channel located above the fuel-supply channel or channels. The waste-gases are thus compelled 85 to pass in a larger proportion through the auxiliary air-supply channels located slightly above the level of the molten metal, and thus I insure the passing of the flame close to the surface of the metal, even at the outlet side of the furnace.

The advantages pointed out above are also secured when auxiliary air-supply channels of the character set forth are applied to reverberatory furnaces (Martin, Talbot, or the like) heated by means of producer gases. 100 In this case the provision of the auxiliary air-supply channels saves the furnace arch and the furnace heads from excessive wear, and besides, the combustion is improved and the interval between charging operations is 105 shortened.

In the accompanying drawings I have illustrated the application of my invention to a Martin furnace, it being understood that this is only an example, and that the 110 invention may be carried out in many other ways.

Figure 1 is a longitudinal vertical section taken chiefly on line 1—1 of Fig. 2, but some parts are shown in section on lines 1^a—1^a and 1^b—1^b respectively of Fig. 2; Fig. 2 is a vertical cross section on line 2—2 of Fig. 1, drawn upon an enlarged scale; Fig. 3 is a vertical cross section taken on line 3—3 of Fig. 1 and showing the furnace head upon an enlarged scale; Fig. 4 is, in its upper part, a cross section on line 4—4 of Fig. 1, and in its lower part, a cross section on line 4^a—4^a of Fig. 1, the entire view being on a larger scale than Fig. 1; and Fig. 5 is a vertical section on line 5—5 of Fig. 1.

The central part 1 of the furnace has its interior chamber 2 bounded above by the arch 3 and below by the trough-shaped bottom 4 which receives the molten metal. This furnace part 1 is supported by means of carriers 5 and posts 6 upon a base or foundation 7. The two furnace heads 8, of like construction, are mounted on trucks 9 having wheels 10 adapted to travel on stationary tracks 11, so that each of the furnace heads may be moved away from the central furnace part 1, which arrangement will facilitate repairs considerably.

At the ends of the furnace regenerators 12 are provided in the base of the furnace, these regenerators serving to heat the air intended to support combustion. The regenerators contain the customary checker-work and are adapted to be connected alternately with a chimney and directly with the surrounding air, by means of a reversing valve of any well-known or approved construction. Such valve is not shown in the drawings. Two channels 13 (Figs. 1 and 2) lead upward from each of the regenerators 12. When the furnace heads 8 are in their operative position (against the central part 1), the channels 13 communicate with two vertical channels 14 provided in each of the heads 8, and these channels 14 are connected with a transverse air-distributing channel 15 located in the upper portion of each head 8. From this transverse channel 15, the main air-supply channel 16 is extended downward at a greater or smaller inclination within the head 8 to the chamber 2 of the furnace.

Beneath each of the main air-supply channels 16 the furnace heads contain slit-like fuel-supply channels 17, each head being provided with three such channels 17, open at one end to the chamber 2 and connected at the other end with a gas conduit 20 secured to the head by means of brackets 19 (Fig. 4). The gas conduit 20 is connected with a stationary supply pipe or main 22, a valve 21 controlling this connection. When one of the furnace heads is to be moved away from the central part 1, the screws 23 holding the flanges 24 are taken

off, thus disconnecting the conduit 20 from the valve 21.

In each of the furnace heads 8, four slit-like auxiliary air-supply channels 25 lead downward at an incline, from the main air-supply channel 16 and from the air-distributing channel 15, to the chamber 2. The lower portions or surfaces 26 of these auxiliary channels 25 are at the same level as the lower surfaces of the fuel-supply channels 17, so that the lower portions of the channels 25 are situated laterally of the channels 17 and, like the latter, have their orifices in the furnace chamber 2 immediately above the surface of the molten metal. The channels 17 and 25 are so arranged in the head 8 that an auxiliary air-supply channel 25 will follow a gas-supply channel 17, in regular alternation. (See Fig. 3).

On the upper surfaces 28 of those head portions which lie between the auxiliary air-supply channels 25, dampers or throttling devices 29 are provided. When air to support combustion passes through the respective channel 16, these throttling devices are retracted to such an extent that they will project from openings 30 provided in the head and receiving said devices with a tight fit. When however the waste-gases are to pass out through the channel 16, the throttling devices are pushed in on the surfaces 28 to such an extent that their front edges, facing the center of the furnace, will register with the outer end of the channel 16, that is to say, such devices will in this case lie at the junction of the channels 15 and 16, as shown at the right in Fig. 1; at the left, Fig. 1 illustrates the position first referred to above. With the throttling devices 29 in their inner positions, the openings 30 are closed by means of tightly fitting removable plugs 31. Eyes 32 and 33 respectively are provided on the dampers 29 and plugs 31 (Fig. 4), so that hook-like tools, introduced from the outside, may be employed to shift the dampers and plugs to the desired position.

The Martin furnace described above is operated as follows: In the position shown in Fig. 1 the gas valve 21 at the left-hand portion of the furnace is open and the gas valve 21 at the right is closed. The reversing valve (not shown) connected with the two regenerators 12 is adjusted to connect the lefthand regenerator 12 directly with the surrounding air and the right-hand regenerator 12 with the chimney. The throttling devices 29 of the left furnace portion are retracted as described, and the throttling devices of the right-hand portion of the furnace are pushed in or forward (see Fig. 1). The air preheated in the left-hand regenerator 12 by contact with the checker-work heated by the passage of the waste-

gases during the preceding period, travels upward in the corresponding channels 13 of the furnace base, and passing through the corresponding air-distributing channel 15, reaches the main air-supply channel 16 and the auxiliary air-supply channels 25 of the left-hand head 8. Through the channels 16, 25 the air for supporting combustion flows into the furnace chamber 2, and becoming mixed with the gas entering through the gas-supply channels 17 of the left-hand head, it is consumed with such gas.

It will be observed that the air streams into the furnace chamber 2 not only through the main air-supply channel 16 situated above the gas-supply channels 17, but further through the auxiliary air-supply channels 25 located laterally of the gas-supply channels 17, or between adjacent gas-supply channels. I thus secure a very thorough mixture of the air with the gas and as complete a combustion as possible, within the furnace proper.

In the furnace chamber 2, the flame travels to the right-hand side of the furnace, close to the surface of the molten metal. The waste-gases escape through those channels of the right-hand furnace head which during the preceding operation have served as air-supply channels, and thus reach the regenerator 12 at the right-hand side. The waste-gases travel not only through the upper main air-supply channel 16 of the right-hand furnace head 8, but a large portion of these gases passes through the auxiliary air-supply channels 25 of the right-hand furnace head. This prevents the flame from rising in the right-hand portion of the furnace chamber 2 and destroying its roof or arch. On the contrary, the flame is compelled to travel close to the surface of the metal, in the right-hand portion of the furnace chamber also. This direction of the flame is further assisted in the right-hand portion of the furnace by the dampers or throttling devices 29, which at the right-hand head 8 are pushed in to the junction of the air-distributing channel 15 with the main air-supply channel 16. These devices throttle the passage of the waste-gases through the channel 16, so that the larger portion of the waste-gases will tend to take its path through the auxiliary air-supply channels 25 located immediately adjacent to the surface of the molten metal; the flame will thus be held down to the surface of the metal, throughout the furnace chamber 2. By adjusting the throttling devices 29, the proportion of gases passing through the main air-supply channel 16 may be regulated as required. During the next period of operation (that is to say, after reversal of the regenerator connections), the course of air, fuel, and waste-gases is similar, the flow being however from right to left, air and

gas entering through the channels 16, 25 and 17 respectively of the right-hand furnace head 8, while the waste-gases leave through the channels 16, 25 of the left-hand furnace head.

The number of gas-supply channels 17 and of auxiliary air-supply channels 25 may be varied without affecting the spirit of my invention.

The construction, arrangement, and number of the throttling devices 29 may be modified in various ways.

The above-described arrangement of auxiliary air-supply channels 25 may be employed with advantage in the case of Martin furnaces, Talbot furnaces, or like reverberatory furnaces, not only in the event of preheating the air alone, as in the example described, but also in cases where both gas and air are preheated in regenerators.

I claim as my invention:

1. A reverberatory furnace provided in its head with a fuel-supply channel, a main air-supply channel located at a higher level than the said fuel-supply channel, and auxiliary air-supply channels located at each side of the fuel-supply channel, at practically the same level therewith.

2. A reverberatory furnace provided in its head with a fuel-supply channel, a main air-supply channel located at a higher level than the said fuel-supply channel, auxiliary air-supply channels located laterally of the fuel-supply channel at each side thereof and at practically the same level therewith, and an adjustable device for throttling the passage of waste-gases through the main air-supply channel.

3. A reverberatory furnace provided in its head with lower channels located at practically the same level, alternate channels being connected with a supply of fuel and of air respectively; and an additional air-supply channel located at a higher level than the said lower channels.

4. A furnace of the reversible regenerative type, provided with a flame chamber and with channels located at each side of said chamber and opening directly into said chamber at different levels, said channels being adapted to serve alternately, during successive operations, for the supply of air and for the escape of combustion products respectively, and additional channels, located laterally of the lower ones of the first-named channels and at practically the same level therewith, said additional channels being adapted to serve for supplying fuel.

5. A furnace of the reversible regenerative type, provided with a flame chamber and with channels located at each side of said chamber and at different levels, said channels being adapted to serve alternately, during successive operations, for the supply

- of heated air and for the escape of combustion products respectively, additional channels, adapted to supply fuel to said chamber, located laterally of the lower ones of the 5 first-named channels and at practically the same level therewith, and regulating devices for variably proportioning the amounts of combustion products flowing through the upper and the lower channels respectively.
- 10 6. A furnace of the reversible regenerative type, provided with a flame chamber and with channels located at each side of said chamber and at different levels, said channels being adapted to serve alternately, 15 during successive operations, for the supply of heated air and for the escape of combustion products respectively, additional channels, adapted to supply fuel to said chamber, located laterally of the lower ones of the 20 first-named channels and at practically the same level therewith, and throttling devices located in the upper channels, for variably proportioning the amounts of combustion products flowing through the upper and 25 the lower channels respectively.
7. A reverberatory furnace provided with

a flame chamber and with channels connected directly with opposite ends of said chamber, each set of channels comprising an upper channel which at one end of the furnace serves for the main supply of air, and at the other end for the escape of a portion of the waste-gases, each set also comprising lower channels located side by side at practically the same level, the lower channels at 30 one end of the furnace serving, in alternate arrangement, for the supply of fuel and for an auxiliary air-supply, while at the other end of the furnace the lower channels corresponding to the auxiliary air-supply channels of the opposite end serve to carry off the other portion of the waste-gases, at a level close to the surface of the material in the flame chamber.

In testimony whereof, I have hereunto set 35 my hand in the presence of two subscribing witnesses.

OSCAR SIMMERSBACH.
